UNITED STATES PATENT OFFICE.

FRANK HENRY ANSON, JR., OF IROQUOIS FALLS, ONTARIO, CANADA.

MACHINE FOR FASTENING TUBULAR LENGTHS.

Application filed January 3, 1922. Serial No. 526,635.

To all whom it may concern:

Be it known that I, FRANK HENRY ANSON, Junior, a citizen of the United States of America, residing at Iroquois Falls, Province of Ontario, Dominion of Canada, have invented certain new and useful Improvements in Machines for Fastening Tubular Lengths, and do hereby declare that the following is a full, clear, and exact description of same.

This invention relates to a machine for fastening tubular lengths of cardboard or other relatively soft material capable of being penetrated by fastening devices and for supporting and manipulating such lengths during the fastening operation.

In the various ways in which tubes of cardboard or other penetrable material are employed, for instance cores for rolls of paper, it has been found expedient to build up a tubular length from shorter lengths placed end to end and an object of the present invention is to provide means for mechanically fastening together tubular lengths in end to end relation. Another object is to incorporate in such machine means whereby the tubular lengths are fastened circumferentially of their adjacent ends. Another object is to provide an automatic stop for discontinuing the operation of the machine upon the completion of a prescribed cycle of operations.

My invention specifically features improved stapling mechanism adapted for stapling adjacent ends of the compound cores or spools upon which roll paper is wound as it passes from a paper making machine, combined with mechanism for supporting and manipulating the tubular lengths in such manner that they are solidly supported during the stapling operation and intermittently freed for mechanical or automatic rotation to the end that successive staples are arranged circumferentially of the core, provision being made for the automatic stoppage of the machine upon the completion of the fastening operation and rotation of the core.

The above objects and features with others will be hereinafter more fully described and particularly pointed out in the appended claims.

For full comprehension, however, of my

invention reference should be had to the accompanying drawings forming a part of this specification, in which the same reference characters indicate like parts and wherein:

Fig. 1 is a side elevation of the tubular length fastening machine;

Fig. 2 is a plan view thereof;

Fig. 3 is an end elevation;

Fig. 4 is an enlarged detail side elevation of the stapling head with the front cover plate removed; and

Fig. 5 is a vertical section on line 5—5 Fig. 4.

Referring now to the drawings, 2 indicates a bed plate at the opposite ends of which are respectively located a pedestal 3 and a post 4, the latter having strapped thereto at 5 one end of a cylindrical bar 6 constituting a support for tubular cores and extending freely towards and in front of the pedestal 3 preferably above the top level of the latter, beneath and just beyond the stapling head or other fastener supplying device of the machine which will be hereinafter described.

The cores 7 to be fastened are received upon the free end of support 6, encircling the latter and positioned with their abutting ends beneath the head of the fastening mechanism which is driven by a horizontal shaft 8 extending between and bearing in the lower portions of the legs of pedestal 3, this shaft being driven by a counter-shaft 9 at the side of and extending rearwardly of the pedestal and supported at its front end in a bearing 10 extending laterally from the pedestal and at its rear end in a bearing 11 upon a rearward extension 12 of the bed plate. An operative connection is established between the shafts 8 and 9 by gears 13 and 14 respectively carried by the shafts, the counter shaft receiving power from a suitable source through loose pulley 15 combined with a clutch 16 with clutch lever 17 fulcrumed upon the bed plate extension and connected by a rod 18 to a starting treadle 19 located at the front of the pedestal.

The fastening mechanism is operated by an eccentric disc 20 upon shaft 8, a connecting rod 21 being strapped to the eccentric, extending upwardly and being connected to

the working parts of the fastening mechanism, the vertical reciprocation of rod 21 actuating said mechanism to insert the fastening devices into the core lengths, such fastenings being clinched upon the bar 6. Preferably the core support 6 is so proportioned that while core lengths are snugly supported thereby, sufficient play is present to permit the lengths turning thereon, means being provided for mechanically rotating the lengths intermittently so that after the insertion of each fastening device the abutting lengths are turned to present a fresh location for the reception of the succeeding fastening. Such rotating means consists preferably of an eccentric disc 22 upon a forward extension of shaft 8 outside the pedestal, such eccentric being connected by an upwardly extending connecting rod 23 to the lower end of a vertical plunger 24 mounted within a guide 24^a upon the front of the pedestal and terminating beneath the support 6. The upper end of the plunger 24 has mounted thereon a dog 25 of bell-crank form pivoted to the plunger and disposed transversely thereof and of the support 6. A spring 26 connected at one end to the plunger and at its opposite end to the inner arm of the dog serves to yieldingly maintain the outer arm of the dog in an outwardly and upwardly extended position with its pointed outer end beneath the support 6, and core thereon so that with each revolution of shaft 8 the consequent vertical reciprocation of the plunger causes the dog to ride upwardly over the core, engage therewith and on the downward stroke of the plunger turn the core through a partial rotation. The outer end of the dog is hooked and carried by the upward stroke of the plunger preferably to a point above the transverse centre line of the support 6, the spring 26 ensuring engagement of the dog with the core. Furthermore the plunger is adapted to intermittently uphold the free end of the support 6 and for this purpose is of a length to engage at the end of the upward stroke beneath the core, it being preferred to form said plunger with a concave head 27 capable of snugly fitting about the underside of the core, the head being adjustably mounted by means of a nut 28 for varying the length of the plunger to suit varying core thicknesses or to meet other requirements of a similar nature.

The eccentrics 20 and 22 are arranged to produce opposed movements upon their respectively actuated members, being disposed on diametrically opposite sides of the shaft 60 so as to effect a downward fastener inserting movement of the fastening mechanism coincidently with an upward movement of the plunger. In this way the core is turned in the periods between succeeding fastener inserting operations and the free end of the

support 6 solidly supported at the moment the stress due to the insertion of the fastener, is placed on the support, this intermittent support of rod 6 effectively bracing the core support when necessary and by the lowering 70 of the head 27, clearing such support of obstruction in readiness for the application of core lengths thereto.

It is preferred to stop the operation of the machine after each operation of inserting a 75 fastener and turning of the core, these operations being effected during each revolution of the drive shaft 8 and for this purpose said shaft is extended rearwardly at 29 to a rear bearing 30 and carries a radial 80 kicker arm 31 projecting from the shaft with its outer end in the path of clutch block 32 carried by clutch ring 33, the kicker being adapted to strike the block each revolution of the drive shaft and throw out the clutch, 85 a spring controlled brake band 34 engaging a brake drum 35 upon extension 29 of shaft 8 and stopping the latter immediately.

I prefer to fasten the core lengths by means of wire staples inserted longitudinally of the adjacent lengths and spanning the joint. For this purpose the hereinbefore mentioned fastening mechanism is exemplified in a staple forming and driving machine of novel construction designed for simplicity 95 and adjustability for use in conjunction with the manipulating mechanism described above.

As will be seen particularly in Figs. 4 and 5, my stapling mechanism consists of a head 100 frame 36 mounted upon pedestal 3 and slidably carrying a vertically disposed column 37 passing downwardly through the top of the pedestal, connected at its lower end to the connecting rod 21 and carrying at its 105 upper end above frame 36, a forwardly extending beam 38. The staple forming and driving mechanism is carried by beam 38 in conjunction with a bracket 39 extending outwardly from the head frame 36, the outer 110 end of such bracket being formed with a housing 39^a presenting a vertical slot 40 in which the former and driver operate. An anvil 41 is located centrally of the slot and at the bottom thereof, being carried or 115 formed upon the bottom of a vertically disposed lever 41^a fulcrumed at its centre upon a horizontally disposed pivot 42 extending transversely of and carried by the bracket 39, the lever being controlled by a spring 43 120 tending to swing the lever horizontally to withdraw the anvil rearwardly from its operative position projecting through an aperture 44 of housing 39^a into the slot 40 of the latter. The staple former consists of 125 a slide 45 in sliding engagement with the edges of the slot, and having a matrix 46 at its lower end constituted by an upwardly extending U-form opening of suitable dimensions to pass snugly over anvil 41 and 130

bend wire over the latter in the formation of a staple, the former being vertically reciprocated by beam 38 as will be presently described. The inferior edges of the matrix and lower end of slide 40 are longitudinally grooved at 46^a for the accommodation of the wire from which the staple is made. This former with its downwardly facing matrix is preferably formed by bifurcating slide 45 at its lower end and positioning a panel 47 between the legs thereof, such panel being of less length than the legs so as to be capable of being located therebetween with its lower end above the ends of the legs to form the interior end of the matrix. This panel 47 constitutes the driver for inserting the staple and is connected to the beam 38 whereby it is actuated to drive the staple. The connection between driver 47 and the beam is preferably effected through the medium of a connecting arm 48 secured at its upper end to the beam and depending therefrom rearwardly of the former and driver, into a rearward extension 49 of the slot 40. The lower end of the connecting arm is fixed at 50 to the upper end of the driver and has a displaceable connection with the former 45 whereby said former is carried down with the driver for the preliminary portion of the stroke to form the staple and is then disconnected, the driver continuing downward to drive the staple. The displaceable connection consists preferably of a latch 51 pivoted at its upper end to connecting arm 48 and having a jaw constituted by a notched corner 52 adapted to engage with the top of former 45, a spring 53 connected at its ends to the latch 51 and arm 48 respectively, normally pressing the latch inwardly into the path of the former and in engagement therewith. An outstanding projection or pin upon the lower end of the latch is adapted to be engaged by a stationary part, for instance the housing 39^a, when the former has been carried down to form the staple, such engagement swinging the latch out from the former 45 and disconnecting it from the connecting arm 48. For convenience of assembly, the bracket 39 is provided with a front cover plate 55 bolted over slot 40 and the stationary part encountered by pin 54 is constituted by an upward extension 56 of this cover plate, the outer corner of the extension being bevelled to form a cam surface in the path of the pin to move the latch laterally out from the former 45 against the influence of spring 53. The former 45 is connected at its upper end to a downwardly expanding spring 45^a carried upon beam 38 which holds said former in its lowermost position during the driving of the staple to guide the latter as it is being driven and to maintain such position of the staple former during the initial upward travel of the arm 48

to ensure the engagement of the latch 51 over the top of the former 45 through the influence of spring 53, the former being then carried upward by the engagement of the top of driver 47 therewith. The connecting arm 48 is preferably in the form of a plate as shown and is formed with a centrally located longitudinal slot or aperture 57 through which a nose 58 formed upon the upper end of lever 41^a is adapted to be protruded by spring 43. The nose 58 extends forwardly over the top of the housing 39^a into engagement with arm 48 to hold the upper end of lever 41^a outwardly from the housing and cause the lower end of the lever to project the anvil through aperture 44 into operative position beneath the staple former. The relative position of aperture 57 and the matrix is such that when the staple is formed the aperture is aligned with nose 58 thus permitting spring 43 to withdraw the matrix, the cam 56 at this time acting to disconnect the former from connecting arm 48. The rear face of housing 39^a is vertically inclined in opposite directions from the centre as shown at 59 to provide ample accommodation for the swinging movement of lever 41^a and the lower surface of nose 58 and bottom of aperture 57 are correspondingly inclined to facilitate the movement of the nose into and out of the aperture.

A reel 60 rotatably carried upon post 4 supplies wire for the stapling mechanism, the wire indicated at 61, being threaded beneath a grooved vertically disposed feed roll 63 rotatably mounted upon an extension 64 of housing 39^a, through an apertured wire block 65 upon the extension, along the grooved top of a cutter 66, transversely across the slot 40 above aperture 44 and anvil 41. The cutter 66 is carried by the extension 64 near the lower end of slot 40 with its inner end just within the latter and its upper inner edge just above the top level of anvil 41 constituting a shear cooperating with the adjacent leg of the former to sever the requisite length of the wire in the formation of the staple. A set screw 67 provides means for moving the cutter longitudinally to adjust its position with respect to the slot 40. A spring pressed idler 68 holds the wire in engagement with feed roll 63, the latter being intermittently rotated to feed the wire forward by means of a spring controlled pawl 69 depending from an arm 70 extending laterally from beam 38, the pawl engaging the teeth of a ratchet 71 upon the trunnion of the feed roll. The downward movement of beam 38 causes the pawl to ride over the ratchet to a position in readiness to engage one of the teeth and rotate the roll during the upward movement of the beam, a stop 72 limiting the downward travel of the pawl and a pin and slot con-

nection 73 between arm 70 and the pawl accommodating continued movement of the arm.

With reference to the foregoing description, the operation of my improved fastening machine is briefly as follows:

Two core lengths are passed over rod 6 with their abutting ends beneath anvil 41 and the machine started by pressure upon 10 treadle 19, the eccentric 20 functioning to drive the staple former downwardly, sever the wire and form the staple, the nose 58 of anvil lever 41^a then projecting into aperture 57 to withdraw the anvil and the 15 latch 51 engaging cam 56 to disengage the former 45 which remains stationary while the driver 47 continues downwards and drives the staple into the abutting ends of the core lengths across the joint the ends of 20 the staple being clinched against bar 6. Meanwhile the eccentric 22 moves head 27 up into engagement with the core lengths to adequately support the bar 6 against the driving strain and to engage dog 25 with 25 the core. The eccentrics then act to raise the staple former and driver and lower the head 27 thus resetting the staple mechanism ready for the formation and driving of a 30 succeeding staple, causing the pawl 69 to rise and rotate roll 63 to feed the wire forward and drawing the dog 25 down to turn the joined core lengths whereby a new location, for the succeeding staple so presented and spaced from the first circumferentially 35 of the core. The kicker 31 is timed to throw out the clutch at this time, the disconnected drive shaft being stopped by brake 34.

The above described cycle is continued until the joined core lengths have been 40 turned through one revolution and staples placed at intervals circumferentially thereof, the composite core being built up by placing additional core lengths upon bar 6 and fastening them as above described 45 to the adjacent ends of the preceding lengths until the desired length is obtained.

What I claim is:

1. In a machine for fastening tubular lengths, the combination with fastener inserting mechanism of a support encircled by 50 and upholding a tubular length adjacent the fastening mechanism and positively actuated mechanism for engaging and turning the length with respect to the support and while 55 upon the latter whereby a new location for succeeding fasteners is presented circumferentially of the tubular length.

2. In a machine for fastening tubular lengths, the combination with fastener inserting mechanism, of a support, encircled by 60 and upholding a tubular length adjacent the fastening mechanism, mechanism for turning the length with respect to the support and while upon the latter whereby a new location for succeeding fasteners is pre- 65

sented circumferentially of the tubular length, means for driving said mechanisms and an automatic device for stopping said driving means upon the completion of a prescribed cycle of operations.

3. In a machine for fastening tubular lengths, the combination with fastener inserting mechanism, of a support for a tubular length adjacent the fastening mechanism, such support having one end free for the unobstructed application thereto of the tubular length and an automatically operated device for intermittently upholding the free end of the support.

4. In a machine for fastening tubular lengths, the combination with fastener inserting mechanism, of a support for a tubular length adjacent the fastening mechanism, such support having one end free for the unobstructed application thereto of the tubular length, an automatically operated holder for intermittently upholding the free end of the support and operating means for the fastener inserting mechanism and said holder, said operating means bringing the holder into upholding position during the fastener inserting period.

5. In a machine for fastening tubular lengths, the combination with fastener inserting mechanism, of a support for a tubular length and extending across the fastening mechanism and being free and unobstructed adjacent the latter for the reception of tubular lengths, means for permanently upholding one end of the support and mechanism for intermittently upholding the free end of the support.

6. In a machine for fastening tubular lengths, the combination with fastener inserting mechanism, of a support for the tubular lengths adjacent the fastening mechanism, such support being upheld at one end and having its opposite end free adjacent the fastening mechanism, mechanism for intermittently upholding the free end of the support, mechanism for turning the tubular lengths while upon the support, driving means for operating said fastening, upholding and turning mechanisms and an automatic stop for discontinuing the operation 105 of the driving means upon the completion of a prescribed cycle of operations of said mechanisms.

7. In a machine for fastening tubular lengths, the combination with fastener inserting mechanism, of a support for the tubular lengths adjacent the fastening mechanism, such support being upheld at one end and having its opposite end free adjacent the fastening mechanism, mechanism for intermittently upholding the free end of the support, mechanism for turning the tubular lengths while upon the support and driving means for operating said fastening, upholding and turning mechanisms.

8. In a machine for fastening tubular lengths, the combination with fastener inserting mechanism, of a support for the tubular lengths adjacent the fastening mechanism, and means for driving the said mechanism, including a drive shaft operatively connected to the mechanism, a counter-shaft operatively connected to the drive shaft, a clutch controlling the counter-shaft, a treadle for throwing in the clutch, a kicker upon the drive shaft and adapted to throw out the clutch and a brake acting upon the drive shaft.
9. In a machine for fastening tubular lengths, the combination with fastener inserting mechanism including a reciprocating element, of a support for the tubular lengths adjacent the fastening mechanism and means for driving said mechanism, including a drive shaft, a connecting rod between the drive shaft and reciprocating element of the fastening mechanism, means upon the drive shaft to impart a reciprocatory movement to the connecting rod, a counter-shaft operatively connected to the drive shaft, a clutch controlling the counter-shaft, means for throwing in the clutch and means for automatically throwing out the clutch.
10. In a machine for fastening tubular lengths, the combination with fastener inserting mechanism, of a support for the tubular lengths adjacent the fastening mechanism, a drive shaft for operating the mechanism, a movable device for upholding one end of the support and means for reciprocating said device into and out of supporting position including a connecting rod between the drive shaft and said device and means upon the drive shaft for imparting a reciprocatory movement to the connecting rod.
11. In a machine for fastening tubular lengths, the combination with a support for the tubular lengths, of automatically and positively actuated mechanism for intermittently engaging and turning the tubular lengths while upon the support, a wire supply and means for automatically forming staples from said wire and driving said staples into the tubular lengths in the intervals between the turning movements of the latter.
12. In a machine for fastening tubular lengths, the combination with a support for the tubular lengths, of automatically and positively actuated mechanism for intermittently engaging and turning the tubular lengths while upon the support, a wire supply, means for automatically forming staples from said wire and driving said staples into the tubular lengths in the intervals between the turning movements of the latter and common driving mechanism for the turning means and staple forming and driving means.
13. In a machine for fastening tubular lengths, the combination with fastener inserting mechanism including a reciprocatory element, of a support for the tubular lengths and having one end free adjacent the fastening mechanism, a reciprocatory device for intermittently upholding the free end of the support, a drive shaft, a connecting rod between the drive shaft and reciprocating element of the fastening mechanism, a connecting rod between the drive shaft and reciprocating device and means upon the drive shaft for imparting opposed reciprocatory movements to said connecting rods respectively.
14. In a machine for fastening tubular lengths, the combination with fastener inserting mechanism including a reciprocatory element, of a support for the tubular lengths and having one end free adjacent the fastening mechanism, a reciprocatory device for intermittently upholding the free end of the support, a drive shaft, a connecting rod between the drive shaft and reciprocating element of the fastening mechanism, a connecting rod between the drive shaft and reciprocating device, means upon the drive shaft for imparting opposed reciprocatory movements to said connecting rods respectively and means for automatically stopping the drive shaft upon the completion of each revolution thereof.
15. In a machine for fastening tubular lengths, the combination with fastener inserting mechanism, of a support for the tubular lengths adjacent the fastening mechanism, a drive shaft for operating the mechanism, a device for engaging with and turning the tubular lengths while upon the support and means for reciprocating said device to engage with and turn the tubular lengths, including a connecting rod between the drive shaft and said device and means upon the drive shaft for imparting a reciprocatory movement to the connecting rod.
16. In a machine for fastening tubular lengths, the combination with fastener inserting mechanism including a reciprocatory element, of a support for the tubular lengths and having one end free adjacent the fastening mechanism, a reciprocatory device for engaging with and turning the tubular lengths while upon the support, a drive shaft, a connecting rod between the drive shaft and the reciprocatory element, a connecting rod between the turning device and drive shaft, and means upon the drive shaft for imparting opposed reciprocatory movements to said connecting rods, respectively.
17. In a machine for fastening tubular lengths, the combination with fastener inserting mechanism including a reciprocatory element, of a support for the tubular lengths and having one end free adjacent the fastening mechanism, a reciprocatory device for

engaging with and turning the tubular lengths while upon the support, a drive shaft, a connecting rod between the drive shaft and the reciprocatory element, a connecting rod between the turning device and drive shaft, means upon the drive shaft for imparting opposed reciprocatory movements to said connecting rods, respectively, and means for automatically stopping the drive shaft upon the completion of each revolution thereof.

18. In a machine for fastening tubular lengths, the combination with fastener inserting mechanism and a drive shaft for operating said mechanism, of a support for the tubular lengths, extending beneath and having one end free adjacent the fastening mechanism, a plunger mounted beneath the free end of the support, an eccentric upon the drive shaft and a connecting rod between the eccentric and plunger whereby the latter is reciprocated into and out of upholding position with respect to the free end of the support.

19. In a machine for fastening tubular lengths, the combination with fastener inserting mechanism and a drive shaft for operating said mechanism, of a support for the tubular lengths extending adjacent the fastening mechanism, a plunger mounted adjacent the support, a dog carried by the plunger and adapted to engage with the tubular lengths and turn the latter while upon the support, an eccentric upon the drive shaft and a connecting rod between the eccentric and plunger whereby the latter is reciprocated to carry the dog into engagement with and cause it to turn the tubular lengths.

20. In a machine for fastening tubular lengths, the combination with fastener inserting mechanism and a drive shaft for operating said mechanism, of a support for said tubular lengths, extending beneath and having one end free adjacent the fastening mechanism, a plunger mounted beneath the free end of the support and presenting a concaved upper end adapted to intermittently

uphold said free end of the support, a spring controlled dog pivoted upon said plunger and adapted to engage with and turn the tubular lengths while upon the support, an eccentric upon the drive shaft and a connecting rod between the lower end of the plunger and the eccentric whereby the former is reciprocated.

21. In a machine for fastening tubular lengths, the combination with fastener inserting mechanism having a reciprocatory element, and a support for the tubular lengths, extending beneath and having one end free adjacent the fastening mechanism, a drive shaft, an eccentric upon the drive shaft, a connecting rod between the eccentric and the reciprocatory element of the fastening mechanism, a plunger mounted beneath the free end of the support and presenting a concaved upper end adapted to intermittently uphold said free end of the support, a spring controlled dog pivoted upon said plunger and adapted to engage with and turn the tubular lengths while upon the support, a second eccentric upon the drive shaft and disposed diametrically opposite with respect to the first mentioned eccentric, a connecting rod between the second eccentric and the plunger, means for operating the drive shaft including a counter-shaft, gearing between the drive shaft and counter shaft, a loose drive pulley upon the counter shaft, a clutch for connecting the pulley to the counter shaft and including a clutch block, a treadle for throwing in the clutch, and means for automatically stopping the drive shaft including a kicker upon and extending outwardly from the drive shaft in position to engage with said clutch block to throw out the clutch upon the completion of each revolution of the drive shaft and a brake acting upon the drive shaft to stop the latter subsequent to the throwing out of the clutch.

In testimony whereof I sign my name to this specification.

FRANK HENRY ANSON, JR.
